UNITED STATES PATENT OFFICE.

ROBERT F. METCALFE, OF ERIE, PENNSYLVANIA, ASSIGNOR, BY MESNE ASSIGNMENTS, TO SOCONY BURNER CORPORATION, OF WILMINGTON, DELAWARE, A CORPORATION OF DELAWARE.

CONTROL APPARATUS.

Application filed March 5, 1923. Serial No. 622,860.

To all whom it may concern:

Be it known that I, ROBERT F. METCALFE, a citizen of the United States, residing at Erie, in the county of Erie and State of Pennsylvania, have invented new and useful Improvements in Control Apparatus, of which the following is a specification.

The invention is designed particularly to control burners. With such burners it is usually desirable to have them running in response to certain outside conditions, as for example, room temperature, and to have them off as the room temperature changes. With some kinds of burners, particularly those using liquid fuel it is desirable to provide some means of control which will close off the fuel supply when there is a failure of ignition with a setting of the control apparatus to affect the operation of the burner. Such devices have been attempted and I have illustrated and described one in my application filed Oct. 2nd, 1922, Serial No. 591,768. The present invention is designed to simplify such a control.

The invention is illustrated in the accompanying drawings as follows:

Fig. 1 shows a plan view of the controlling switch and motor.

Fig. 2 a front elevation of the same.

Fig. 3 a side elevation of the burner and operating parts.

Fig. 4 an end elevation of the burner.

Fig. 5 a diagrammatical view of the burner and the elements of control and the operating and controlling members.

1 marks the burner, 2 a fuel jet leading to the burner, 3 an ignition pocket and preliminary burner, 4 a spark plug forming a means of ignition, 5 a fuel supply pipe leading from a source of supply 5^a to the jet 2, 6 the air nozzle of the atomizing jet, 7 a pipe leading from the air nozzle to a pump 8, 9 a piston operating in the pump, and 10 a piston leading from the piston and having a strap 11 operating on an eccentric 12. The eccentric 12 is mounted on a shaft 13. A worm gear 14 is also mounted on the shaft 13 and is driven by a worm 15. The worm 15 is mounted on a shaft 16 which is the rotor shaft of a motor 16^a.

A fan 17 is mounted on the shaft 16. This

is arranged in the fan case 18 and connected by a pipe 19 with the air inlet passage 20 leading to the burner, the passage 20 communicating by a passage 21 around the end 55 of the ignition chamber 3 and leading into the burner proper 1. It will be seen, therefore, that as the pump is put in operation supplying air under high pressure through the pipe 7 to the atomizing jet the fan 17 is 60 at the same time put in motion supplying the volume of air for combustion.

The line wires 22 and 23 extend to the burner motor, the line 23 being connected by a wire 24 with one of the brushes 26. A 65 wire 27 leads from the wire 22 to a post 28. A switch plate 29 has the contact point 30. A contact point 31 operates in connection with the point 30 as a switch and is mounted on a plate 32. The plate 32 is carried by 70 a post 33. The post 33 is connected by a wire 34 with a brush 35 of the motor 16^a. When, therefore, the contact point 31 is moved into contact with the point 30 line current is delivered to the motor and 75 the burner motor operates to continue the burner in running condition so long as the room conditions, or other conditions remain so as to make the running condition desirable.

The plate 32 has a cam riding projection 36 which operates on a cam 37. The cam 37 is mounted on a controlling switch shaft 38. It is provided with a notch 39 which lets the projection drop so as to break the connection 85 through the contacts 31-30 and a riding surface 40 which holds these points in contact.

A contact point 41 is mounted on the plate 32, being insulated therefrom, and operates 90 in connection with a point 42 to form a switch which is closed when the switch with the contacts 31-30 is closed. The point 41 is connected by a wire 43 with a bridge plate 44 and this plate is connected by a wire 45 95 with a spark coil 46. A wire 47 leads from the coil 46 to the spark plug 4, being grounded in the usual manner at the spark plug and through a ground 48. A wire 49 leads from the coil to a breaker plate 50 which is 100 actuated by a breaker cam 51 on the rotor shaft 16. The breaker plate 50 operates a

switch in connection with the breaker post 52 which is grounded at 53. Consequently when the burner motor is running the breaker is running. The contact point 42 is carried by a spring plate 54 mounted on a post 55. A wire 56 leads from the post 55 to a wire 57. The wire 57 leads from a transformer 58 which is energized by wires 59 and 60 leading from and to the wires

10 22—23.

A worm gear 61 is mounted on the shaft 38 and is driven by a worm 62. The worm 62 is mounted on a rotor shaft 63 of the control motor 64. A wire 65 extends from 15 the transformer 58 to one post of the control motor and a wire 66 leads from the opposite post to the ground. A fan 67 is arranged on the rotor shaft 63 to reduce the control speed of the motor to some extent.

20 In operating the device the control motor operates the controlling switch, the controlling switch as it moves forward breaking the circuit through the control motor so that the burner switch 30—31 is maintained either in open or closed position at 25 the different stops as the control motor circuit is opened. In the present invention the circuit operating the controlling motor is directly controlled by the controlling switch without the intervention of relays or 30 other locking devices and this is made possible by the construction of the switch. Further it is possible with this construction to use but one circuit from some of the controlling elements as distinguished from the 35 double lines of my prior application. A brush arm 68 is fixed on the shaft 38 and insulated and grounded by any convenient means, as by a wire 71. It has the brushes 40 69 and 70. These brushes traverse a series of switch plates which may be designed as the normal running or on plate 72, the emergency stop or off plate 73, the starting or retarding plate 74, the emergency plate 75, 45 and the emergency stop plate 76. The running plate 72 is connected with the extensions circumferentially from the emergency stop plate 76 having a radial position coincident with the plate 75 and the brushes 69 50 and 70 extend over these two plates simultaneously when the arm reaches a position to bring the brushes in register with them.

In the operation of this switch, starting with the brushes in the normal stop position, 55 or off position on the plate 73 as shown, when the thermostatic control reaches the cold side the current is connected through the control motor, and advances the brushes off the plate 73 on to the plate 74. The 60 plate 74 continues the connection through the control motor so that the control motor continues running until the brush is brought over the plates 72 and 75. If the burner has started and is running normally the connection through the plate 75 will be broken and

there will be no connection through the plate 72. The thermostatic control reaches the warm side. When this happens the brush moves forward off the plates 72 and 76 on to the plate 73 the stopped position. If, however, when the brush reaches a position over the plates 72—75 by reason of a lack of normal conditions in the burner a connection is established through the plate 75 and the motor is continued until the brush is brought 75 off the plate 75 to the emergency stop position 76 where it is locked and remains until it may be manually started. This briefly gives an outline of the operation of the switch. The various circuits and elements for accomplishing this are as follows:

The thermally responsive element 77 operates between the cold contact plate 78 and the hot contact plate 79 ordinarily referred to as the hot and cold side of the thermostatic switch. A wire 80 extends from the cold side to a bridge plate 81 and this is connected by a wire 82 with the stop plate 73. A wire 83 extends from the element 77 to the wire 57. A wire 84 leads from the wire 57 to a bridge plate 85 and a wire 86 leads from the bridge plate 85 to the starting plate, 74. It will readily be seen, therefore, as the thermal element reaches the cold side 79 with the brushes in the position shown in Fig. 5 a circuit is established by way of the ground, brushes, plate 73, wire 82, bridge 81, wire 80, through the thermostat, wire 83, wire 57, 65, the motor, and ground 66, and this starts the controlling motor moving the brush on to the starting plate 74. Here the circuit is continued by the wire 86 connecting with the wire 57, the circuit being otherwise the same. The brushes 69 and 70 so operate on the plates as to establish a contact with the succeeding plate before leaving the preceding plate. Thus a circuit is established through the plate 74 before it is broken through the plate 73.

110 The brush moves forward on to the plate 74 and at the same time the cam 37 advances moving the surface 40 under the projection 36 so as to close the switch 31—30 and start the burner motor. The same action energizes the spark plug and prepares for ignition. The plate 74 is sufficiently long at the speed of the motor to give the burner ample time for ignition and for assuming approximately normal conditions before the brush reaches the plate 72—75. As the brush passes off of the plate 74 on to the plates 72—75 if the conditions are normal the circuit through the control motor is opened and the control motor stops leaving the projection 36 on the surface 40 and the switch 30—31 closed. The burner motor, therefore, continues to operate until the thermal element 77 reaches the hot side 78. The hot side 78 is connected by a wire 89 with the

emergency plate 76 from which the running plate 72 extends. The brush remains on the plate 72 until the closing of the warm side of the switch 77—78 when a circuit is established by way of the brush and its ground and through the thermal element, wire 83, wire 57 to the control motor. The control motor, therefore, under these conditions is started and the brush is moved forward until the circuit is broken by the brush moving off on to the stop plate 73.

When the brushes reach the point over the plate 76 the projection 36 drops off the surface 40 and opens the motor switch. Thus the control motor will alternately advance the brush responsive to changes of temperature of the thermostat so long as normal conditions prevail. When, however, there is a failure of ignition either by lack of fuel or failure of the spark plug it becomes very essential that the burner be stopped and it is, therefore, desirable to prevent the stopping of the brushes 69—70 on the running plate 72. For this reason the emergency plate 75 is provided which is covered by the brush simultaneously with the plate 72 and this forms a connection through a switch responsive to burner conditions. I prefer the switch here shown but in a general way any switch responsive to burner conditions may be used. A passage 90 extends from the burner chamber and is responsive to burner chamber pressures. This terminates in an insulated ring 91 in which is mounted the shutter or flapper 92. The flapper is hinged at 93 and free to swing outwardly when subjected to pressure from the burner chamber, the amount of resistance being regulated by a screw weight 94. The flapper when free from the burner pressure rests on a contact post 95. This post is connected by a wire 96 with the wire 57 which is, as before described, in circuit with the controlling motor. A wire 97 is connected with the flapper 92 by way of the hinge and extends to a bridge plate 98 which is connected by a wire 99 with the plate 75.

The operation of this safety switch is as follows:—If there is ignition in the burner there is immediately created a pressure due to expanding gas which is delivered to the flapper and this moves the flapper outwardly out of contact with the post 95, thus breaking the connection from the plate 75 to the wire 57. Consequently when the brush reaches the plate 75, the circuit through the plate 72 being opened, there is no circuit leading to the control motor and the control motor stops and the brush remains on the running plate with the switch 30—31 closed so that the burner may continue running until altered by the thermal conditions operating on the thermostatic element 77. If, however, there is a failure of ignition and a consequent failure of pres-

sure in the burner chamber, the flapper 92 remains in contact with the post 95 and a circuit is established between the plate 75 and the wire 57 and consequently through the control motor. As a result the control motor does not stop when the brush passes from the plate 74 to the plates 72—75 but continues until the brush passes off the plate 75 on to the plate 76. This is termed the emergency stop position and the motor being out of circuit when the brush reaches this position it stops. In this position the projection 36 is dropped off the surface 40 and the switch 30—31 is opened so that the burner motor is stopped and at the same time, as a matter of economy, the ignition circuit is opened by opening the switch 41—42.

When the conditions of the burner are satisfied it is desirable to be able to start the device conveniently and this can be done by closing the connection through the emergency stop plate 76. A push button switch 100 is operated by a push button 101, the switch 100 being connected by a wire 102 with a wire 107. The other side of the switch is connected by a wire 103 with a bridge plate 104 and this plate is connected by a wire 105 with the wire 89 and thence with the stop plate 76. When, therefore, the push button is operated a connection is made through the control motor and it is started in action so that the brush is carried over on to the stop plate 73 and either stops there or advances depending on the condition of the thermal element 77.

It will be seen, that there are two normal control circuits leading from the hot and cold side 79 and 78 and that there is a control motor circuit leading through the wire 79 and its branches which is controlled through the control switch, and that there is an emergency circuit through the flapper switch 92. It will also be observed that in the movable element of the switch there are two plates, or switch elements, which are covered simultaneously by the brush or other element of the switch. This overlapping makes it possible to form a device which will move past the safety stop conditions when the burner is in normal condition, in other words, there is no necessity for outside mechanism to accomplish this purpose. Further the brush bridges the contact plate so that the control motor is kept running when started so as to move the brush to a new position.

What I claim as new is:—

1. In a rotating control apparatus, the combination of a control motor; a first normal control connection; a second normal control connection; an emergency control connection; a control motor connection; and a switch actuated by the motor and normally alternating closures through the control motor connection with the normal control con-

- connections and creating with an electric current change in the emergency control connection a response in the control motor connection stopping the motor with the switch in position irresponsible to conditions in the normal connections, said switch maintaining one control motor connection until another control motor connection is established.

2. In a rotating control apparatus, the combination of a control motor; a burner; a burner motor; a first normal control connection; a second normal control connection; an emergency control connection responsive to changes in combustion in the burner; a control motor connection; a switch actuated by the control motor and normally alternately closing the control motor connection with the normal control connections and creating with an electric current change in the emergency control connection a response in the control motor connection stopping the motor with the switch in position irresponsible to the conditions in the normal control connections, said switch maintaining one control motor connection until another is established and means controlled by the control motor controlling the burner motor.

3. In a rotating control apparatus, the combination of a control motor; a first normal control connection; a second normal control connection; an emergency control connection; a control motor connection; a switch actuated by the motor and normally alternating closures through the control motor connection with the normal control connections and creating with an electric current change in the emergency control connection a response in the control motor connection stopping the motor with the switch in position irresponsible to conditions in the normal connections, said switch maintaining one control motor connection until another control motor connection is established; a burner motor; and a switch controlled by the motor controlling the burner motor.

4. In a rotating control apparatus, the combination of a control motor; a first normal control connection; a second normal control connection; an emergency control connection; a control motor connection; a switch actuated by the motor and normally alternating closures through the control motor connection with the normal control connections and creating with an electric current change in the emergency control connection a response in the control motor connection stopping the motor with the switch in position irresponsible to conditions in the normal control connections, said switch maintaining one control motor connection until another control motor connection is established; a burner motor; and a switch controlled by the motor controlling the burner motor.

5. In a rotating control apparatus, the combination of a control motor; a warm side thermally controlled normal control connection; a cold side thermally controlled normal control connection; an emergency control connection; a control motor connection; and a switch actuated by the motor and normally alternately closing the control motor connection with the normal control connections and creating with an electric current change in the emergency control connection a response in the control motor connection stopping the motor with the switch in position irresponsible to the conditions in the normal connections, said switch maintaining one control motor connection until another is established.

6. In a rotating control apparatus, the combination of a control motor; a first normal control connection; a second normal control connection; an emergency control connection; a control motor connection; a switch actuated by the motor and normally alternating closures through the control motor connection with the normal control connections and creating with an electric current change in the emergency control connection a response in the control motor connection stopping the motor with the switch in position irresponsible to conditions in the normal control connections, said switch maintaining one control motor connection until another control motor connection is established; a starting connection; and a manually actuated switch controlling the starting connection, the closing of said switch creating a response in the control connection after the control motor is stopped through a change in the emergency connection.

7. In a rotating control apparatus, the combination of a control motor; a burner; a first normal control connection; a second normal control connection; an emergency control connection responsive to changes in the combustion in the burner; a control motor connection; and a control switch actuated by the motor normally alternately closing the control motor connection with the normal control connections and creating with an electric current change in the emergency control connection a response in the motor, the control connection stopping the motor with the switch in a position irresponsible to conditions in the normal connections, said switch maintaining one control motor connection until another is established.

8. In a rotating control apparatus, the combination of a control motor; a burner; a first normal control connection; a second normal control connection; an emergency control connection responsive to changes in the combustion in the burner; a control motor connection; a control switch

actuated by the motor normally alternately closing the control motor connection with the normal control connections and creating with an electric current change in the emergency control connection a response in the motor, the control connection stopping the motor with the switch in a position unresponsive to conditions in the normal connections, said switch maintaining one control motor connection until another is established; a burner motor; and a burner switch controlling the burner motor, said switch being actuated by the control motor and stopping the burner motor with the control switch in position unresponsive to conditions in the normal connections.

9. In a control apparatus, the combination of a rotating control motor; a motor connection; a first normal control connection; a second normal control connection; an emergency control connection; and a control switch actuated by the motor and adapted to close said control connections with the motor connection to complete a circuit through the motor, said switch acting to normally alternately close the motor connection with the normal control connections, said switch opening the motor connection with a current change in the emergency control connection with the switch in position unresponsive to conditions in the normal connections.

10. In a control apparatus, the combination of a rotating control motor; a motor connection; a first normal control connection; a second normal control connection; an emergency control connection; and a control switch actuated by the motor and adapted to close said control connections with the motor connection to complete a circuit through the motor, said switch acting to normally alternately close the motor connection with the normal control connections, said switch opening the motor connection with a current change in the emergency control connection with the switch in position unresponsive to conditions in the normal connections, said switch maintaining one control motor connection until another is established.

11. In a rotating control apparatus, the combination of a control motor; a burner; a first normal control connection; a second normal control connection; an emergency control connection responsive to variations in condition of combustion in the burner; a motor connection; and a control switch actuated by the motor and normally alternately closing the motor connection with the normal control connection and opening the motor connection with a change in the emergency control connection with the switch in position unresponsive to conditions in the normal connections.

12. In a rotating control apparatus, the

combination of a control motor; a burner; a first normal control connection; a second normal control connection; an emergency control connection responsive to variations in condition of combustion in the burner; a motor connection; and a control switch actuated by the motor and normally alternately closing the motor connection with the normal control connection and opening the motor connection with a change in the emergency control connection with the switch in position unresponsive to conditions in the normal connections, said switch maintaining one control motor connection until another is established.

13. In a rotating control apparatus, the combination of a control motor; a burner; a first normal control connection; a second normal control connection; an emergency control connection responsive to variations in condition of combustion in the burner; a motor connection; a controlling switch actuated by the motor and normally alternately closing the motor connection with the normal control connection and opening the motor connection with a change in the emergency control connection with the switch in position unresponsive to conditions in the normal connections; a burner motor; and a burner switch actuated by the control motor and positioned to stop the burner as the control switch acts in response to the change in the emergency connection.

14. In a rotating control apparatus; the combination of a control motor; a burner; a first normal control connection; a second normal control connection; an emergency control connection responsive to variations in condition of combustion in the burner; a motor connection; a control switch actuated by the motor and normally alternately closing the motor connection with the normal control connection and opening the motor connection with a change in the emergency control connection with the switch in position unresponsive to conditions in the normal connections, said switch maintaining one control motor connection until another is established; a burner motor; and a burner switch actuated by the control motor and positioned to stop the burner as the control switch acts in response to the change in the emergency connection.

15. In a control apparatus, the combination of a rotating control motor; a burner; an emergency switch responsive to changes in the combustion in the burner; a single emergency connection controlled by said switch; a first normal control connection; a second normal control connection; a control motor connection; and a control switch actuated by the control motor and normally alternately closing the control motor connection with the normal control connections and closing the emergency connec-

tion as the emergency switch is actuated to advance the control switch to a position irresponsible to conditions of the normal connections and in position to stop the control motor.

16. In a control apparatus, the combination of a rotating control motor; a burner; an emergency switch responsive to changes in the combustion in the burner; a single emergency connection controlled by said switch; a first normal control connection; a second normal control connection; a control motor connection; a control switch actuated by the control motor and normally alternately closing the control motor connection with the normal control connections and closing the emergency connection as the emergency switch is actuated to advance the control switch to a position irresponsible to conditions of the normal connections and in position to stop the control motor; a burner motor; and a burner switch actuated by the control motor and positioned to stop the burner motor as the control switch is moved in response to the action of the emergency connection.

17. In a control apparatus, the combination of a rotating control motor; a burner; an emergency switch responsive to changes in the combustion in the burner; a single emergency connection controlled by said switch; a first normal control connection; a second normal control connection; a control motor connection; a control switch actuated by the control motor and normally alternately closing the control motor connection with the normal control connections and closing the emergency connection as the emergency switch is actuated to advance the control switch to a position irresponsible to conditions of the normal connections and in position to stop the control motor; a single starting connection; and a normally controlled switch controlling the starting connection, said starting connection acting with the controlling switch to close the control motor connection after the motor has been stopped in response to the action of the emergency control connection.

18. In a control apparatus, the combination of a rotating control motor; a rotary switch actuated by the motor having a brush member and a plate member having relative rotary movement, the plate member having a series of contact plates; a control motor connection; and connections extending from the plates and forming with the control motor connection a control circuit controlling the motor to move the switch when a control connection extending from the plate covered by the brush is closed, one of the plates overlapping another in brush relation and completing the motor circuit to advance the switch over one of the overlapping plates without the closure of the

connection extending from the last-mentioned plate.

19. In a control apparatus, the combination of a rotating control motor; a rotary switch actuated by the motor having a brush member and a plate member, the plate member having a series of contact plates; a control motor connection through the brush; and control connections extending from the plates and forming with the control motor connection a control circuit controlling the motor to move the switch when a control connection extending from a plate covered by the brush is closed, one of the plates overlapping another plate in brush relation and completing a brush connection to actuate the motor to advance the switch over one of the overlapping plates without a closure of the connection extending from the last-mentioned plate.

20. In a control apparatus, the combination of a rotating control motor; a rotary switch actuated by the motor having a brush member and a plate member having relative rotary movement, the plate member having a series of contact plates; a control motor connection; and connections extending from the plates and forming with the control motor connection a control circuit controlling the motor to move the switch when a control connection extending from the plate covered by the brush is closed, one of the plates overlapping another in brush relation and completing the motor circuit to advance the switch over one of the overlapping plates without a closure of the connection extending from the last-mentioned plate, said brush having a relation to the plates closing a connection as it advances with a succeeding plate before breaking the connection with the plate in circuit.

21. In a control apparatus, the combination of a rotating control motor; a rotary switch actuated by the motor having a brush member and a plate member, the plate member having a series of contact plates; a control motor connection through the brush; and control connections extending from the plates and forming with the control motor connection a control circuit controlling the motor to move the switch when a control connection extending from a plate covered by the brush is closed, one of the plates overlapping another plate in brush relation and completing a brush connection to actuate the motor to advance the switch over one of the overlapping plates without a closure of the connection extending from the last-mentioned plate, said brush having a relation to the plates closing a connection as it advances with a succeeding plate before breaking the connection with the plate in circuit.

22. In a control apparatus, the combination of a rotating control motor; a first

normal control connection; a second normal control connection; an emergency control connection; a control motor connection; and a rotary control switch actuated by the motor and having a brush member and a plate member, the plate member having a series of contact plates, one connected with the first control connection, a second connected with the second control connection, and a third connected with the emergency control connection, said plates with their connections closed forming with the control motor connection a motor controlled circuit with the brush on a plate having its connection closed and moving the brush from a plate in circuit, one of the plates connected with one of the normal connections overlapping the plate having the emergency connection in brush relation and completing a circuit controlling the advance of the switch over the emergency plate without a closure of the emergency connection.

23. In a control apparatus, the combination of a rotating control motor; a first normal control connection; a second normal control connection; an emergency control connection; a control motor connection; and a rotary control switch actuated by the motor and having a brush member and a plate member, the plate member having a series of contact plates, one connected with the first control connection, a second connected with the second control connection, and a third connected with the emergency control connection, said plates with their connections closed forming with the control motor connection a motor controlled circuit and moving the brush from a plate in circuit, one of the plates connected with one of the normal connections overlapping the plates having the emergency connection in brush relation and completing a circuit controlling the advance of the switch over the emergency plate without a closure of the emergency connection, the brush extending from one plate to another to complete a connection as it advances with a succeeding plate before breaking the connection with the plate in circuit.

24. In a control apparatus, the combination of a rotating control motor; a thermally actuated cold side normal control connection; a thermally actuated warm side normal control connection; a burner; an emergency control connection responsive to combustion conditions in the burner; a control motor connection; a control switch actuated by the motor, said switch comprising a brush member and a plate member, said members having relative rotary motion, the plate member having a series of plates, an emergency plate connected to the emergency connection, a running plate connected to the cold side normal connection, a stop plate connected with the running plate, and a stop

plate connected with the warm side normal connection, the motor connection acting with the above-mentioned connections when closed to form a motor control circuit, the running plate having an overlapping brush relation in respect to the emergency plate whereby a connection may be made through the cold side normal connection to advance the switch without a closure of the emergency connection.

25. In a control apparatus, the combination of a rotating control motor; a thermally actuated cold side normal control connection; a thermally actuated warm side normal control connection; a burner; an emergency control connection responsive to combustion conditions in the burner; a control motor connection; and a control switch actuated by the motor, said switch comprising a brush member and a plate member, said members having relative rotary motion, the plate member having a series of plates, an emergency plate connected to the emergency connection, a running plate connected to the cold side normal connection, a stop plate connected with the running plate; and a stop plate connected with the warm side normal connection, the motor connection acting with the above-mentioned connections when closed to form a motor control circuit, the running plate having an overlapping brush relation in respect to the emergency plate whereby a connection may be made through the cold side normal connection to advance the switch without a closure of the emergency connection, the brush closing the connection as it advances with a succeeding plate before breaking the connection with the plate in circuit.

26. In a control apparatus, the combination of a rotating control motor; a thermally actuated cold side normal control connection; a thermally actuated warm side normal control connection; a burner; an emergency control connection responsive to combustion conditions in the burner; a control motor connection; and a control switch actuated by the motor, said switch comprising a brush member and a plate member, said members having relative rotary motion, the plate member having a series of plates, an emergency plate connected to the emergency connection, a running plate connected to the cold side normal connection, a stop plate connected with the running plate, and a stop plate connected with the warm side normal connection, the motor connection acting with the above-mentioned connections when closed to form a motor control circuit, the running plate having an overlapping brush relation in respect to the emergency plate whereby a connection may be made through the cold side normal connection to advance the switch without a closure of the emergency connection; and a

starting connection leading to the stop plate closing the circuit as the starting connection is closed.

27. In a control apparatus, the combination of a rotating control motor; a thermally actuated cold side normal control connection; a thermally actuated warm side normal control connection; a burner; an emergency control connection responsive to combustion conditions in the burner; a control motor connection; and a control switch actuated by the motor, said switch comprising a brush member and a plate member, said members having relative rotary motion, the plate member having a series of plates, an emergency plate connected to the emergency connection, a running plate connected to the cold side normal connection, a stop plate connected with the running plate, a stop plate connected with the warm side normal connection, and a retarding plate in the motor connection, the motor connection acting with the above-mentioned connections when closed to form a motor control circuit, the running plate having an overlapping brush relation in respect to the emergency plate whereby a connection may be made through the cold side normal connection to advance the switch without a closure of the emergency connection.

28. In a control apparatus, the combination of a rotating control motor; a thermally actuated cold side normal control connection; a thermally actuated warm side normal control connection; a burner; an emergency control connection responsive to combustion conditions in the burner; a control switch actuated by the motor, said switch comprising a brush member and a plate member, said members having relative rotary motion, the plate member having a series of plates, an emergency plate connected to the emergency connection, a running plate connected to the cold side normal connection, a stop plate connected with the running plate, and a stop plate connected with the warm side normal connection; and a control motor connection through the brush, said motor connection acting with the above-mentioned connections when closed to form a motor control circuit, the running plate having an overlapping brush relation in respect to the emergency plate whereby a connection may be made through the cold side normal connection to advance the switch without a closure of the emergency connection.

29. In a control apparatus, the combination of a rotating control motor; a thermally actuated cold side normal control connection; a thermally actuated warm side normal control connection; a burner; an emergency control connection responsive to combustion conditions in the burner; a control switch actuated by the motor, said switch

comprising a brush member and a plate member, said members having relative rotary motion, the plate member having a series of plates, an emergency plate connected to the emergency connection, a running plate connected to the cold side normal connection, a stop plate connected with the running plate, and a stop plate connected with the warm side normal connection; and a control motor connection through the brush, 70 said motor connection acting with the above-mentioned connections when closed to form a control circuit, the running plate having an overlapping brush relation in respect to the emergency plate whereby a connection may be made through the cold side normal connection to advance the switch without a closure of the emergency connection, and 75 a starting connection leading to the stop plate closing the circuit as the starting connection is closed.

30. In a control apparatus, the combination of a rotating control motor; a thermally actuated cold side normal control connection; a thermally actuated warm side normal control connection; a burner; an emergency control connection responsive to combustion conditions in the burner; a control switch actuated by the motor, said switch comprising a brush member and a plate member, said members having relative rotary motion, the plate member having a series of plates, an emergency plate connected to the emergency connection, a running plate connected to the cold side normal connection, a stop plate connected with the running plate, a stop plate, connected with the warm side normal connection, and a retarding plate in the motor connection; and a control motor connection through the brush, the motor connection acting with the above-mentioned connections when closed to form a motor control circuit, the running plate having an overlapping brush relation in respect to the emergency plate whereby a connection may be made through the cold side normal connection to advance the switch without a closure of the emergency connection.

31. In a control apparatus, the combination of a control motor; a thermally actuated cold side normal control connection; a thermally actuated warm side normal control connection; a burner; an emergency control connection responsive to combustion conditions in the burner; a control switch actuated by the motor, said switch comprising a brush member and a plate member, said members having relative rotary motion, the plate member having a series of plates, an emergency plate connected to the emergency connection, a running plate connected to the cold side normal connection, a stop plate connected with the running plate, and a stop plate connected with the warm 115

side normal connection; a motor connection through the brush, the motor connection acting with the above-mentioned connections when closed to form a motor control circuit, the running plate having an overlapping brush relation in respect to the emergency plate whereby a connection may be made through the cold side normal con-

nection to advance the switch without a closure of the emergency connection, the 10 brush closing the connection as it advances with a succeeding plate before breaking the connection with the plate in circuit.

In testimony whereof I have hereunto set my hand.

ROBERT F. METCALFE.
